(57) **ABSTRACT**

The present invention is a firearm safety device designed to secure a firearm and prevent injury or death by an unauthorized user. The firearm port block is a fitted cylindrical device that when placed in the open port of a firearm prevents the firearm from being discharged. By using a positioning tab the firearm port block is placed in an open port of a firearm, expanded and locked. The open bolt supports one end of the device and the firing chamber houses the other end, blocking live ammunition. The firearm is placed in use by unlocking and removing the port block. The firearm port block is inexpensive to manufacture and easily installed and removed from an open port firearm.

BACKGROUND OF THE INVENTION

Weapons have been used for centuries to protect life and property and aid in sustaining life. Firearms allow our armies and police officers to engage in combat and different confrontations to bring about peace and harmony.

Firearms are a major cause of crime in the world today. Weapons used by young children provide a means for them to conduct mass killings in our schools and on the streets. Criminals injure, maim and kill hundreds of people each year by the use of firearms. Children playing with unsecured weapons are also maimed, injured or killed.

Our government leaders are working diligently to structure gun control laws that will allow us to live in a safer environment. One or more gun control laws being considered are safety locks and safety devices to prevent firearms from firing.

Trigger locks are safety devices used to prevent weapons from being discharged. Most trigger guards do provide a means of safety but are time consuming for someone that is required to use the weapon in an emergency situation. It is dangerous to place a trigger lock on a loaded weapon.

Many safety devices are designed to have a rod inserted in the muzzle and an attachment inserted in the firing chamber connected to the rod and pulled or tightened to swell in the weapons firing chamber. Usually, this is accomplished by twisting the rod clockwise to lock and counter-clockwise to unlock, many are keyed. These type barrel devices are again, time consuming, expensive and could result in injury or death if an apparatus is being installed in a loaded weapon. A person in a hurried situation could conceivably remove the device inserted in the firing chamber and leave the rod in the barrel, chamber a round, and fire the weapon that would result in injury or death to the user.

Many devices have been invented to prevent firearms from being discharged. One such device described in U.S. Pat. No. 4,058,923, to Smith, show a safety clip attached to the handgrip of a shotgun. The clip further extends upward and into the magazine, the clip then curls back and against the shell that is ready to be injected into the firing chamber. This system would prevent semi-automatic and automatic shotguns from being fired if there is no shell present in the firing chamber before the safety clip is installed. Mr. Smith's safety device would be of little use on other firearms. For example, the device could not be mounted to a single barrel firearm or a break-over shotgun.

U.S. Pat. No. 4,654,992, to Layergne, shows a locking apparatus inserted into the magazine of a weapon with a frame extending upward with said frame having a keyed lock, when rotated, positions a lever down and into the ejection port. The art displayed by U.S. Pat. No. 4,654,992, to Mr. Layergne, limits the use of the firearm safety device to magazine type firearms.

U.S. Pat. Nos. 4,965,952 and 5,097,613 to Miller, depicts a loaded, live semi-automatic rifle cartridge, as used by the U.S. Military M-16 Rifle. Further art displays a safety plug designed similar to the M-16's cartridge and manufactured by using certain plastics or alloy materials. The art displays a visual indicator tab protruding from the ejection port that allows visual inspection to determine if a live round has been injected into the firing chamber. The safety plug is of great benefit to allow visual inspection but can be easily removed by opening the breech and manually removing the tab and plug. After removing the plug a child, adult or perpetrator would be allowed to use the weapon.

U.S. Pat. No. 5,231,236, to Del Real, is basically a rack and pinion movable device and relies largely on a key for positioning. This apparatus rests against the weapons bolt on one end and against the outside opening of the weapon's firing chamber on the opposite end. Mr. Del Real's safety device, when in the locked position allows a live shell in the weapon's firing chamber that could possibly be discharged.

Safety plugs, locking mechanisms, gun locking devices and chamber devices are disclosed in U.S. Pat. Nos. 5,014,457, 5,070,635, 4,995,180, 5,038,580, 5,419,069, 5,475,994 and 5,669,252.

It is the objective of the present invention to provide a fast and safe method for securing a firearm by blocking the ejection port and firing chamber.

DISCLOSURE OF THE INVENTION

45 The present invention is an advanced safety device for firearms. The device, when placed in the weapon's loading and ejection port, provides an extremely safe method for securing a firearm and prevents the firearm from being fired. The firearm port block apparatus is very affordable and requires a small expense to the consumer.

50 The firearm port block is a cylindrical device that consists of a canister and a tube and is sized to a weapons particular shell. The canister has a closed end and an open end and is hollow. The closed end of the canister next to the firearm's bolt supports a raised rim. An expandable spring is inserted into the open end of the canister nearest the firing chamber. A cylinder tube smaller in diameter than the open canister end, and having a closed end closest to the canister opening, is inserted inside the canister and against the expandable 55 spring making for expansion and contraction of the cylinder tube inside the canister. A locking mechanism is provided to lock the cylinder in the "extended" or "compressed" position. The apparatus supports a firing cap attached to the expandable cylinder end closest to the weapon's firing chamber.

60 The firearm port block, in the compressed position, is placed into a weapons open port. When released from the

compressed position the expanded firearm port block positions the firing cap into the firing chamber and the opposite end against the bolt. By turning the lock clockwise on the firearm port block the firearm is then in the locked position. The firearm port block is removed by reversing the locked cylinder from the expanded position to the compressed position.

BRIEF SUMMARY OF THE INVENTION

It is an object of the invention to provide a fast, economical and safe method for placing a firearm in an inoperable mode until the weapon is ready for use.

Another object of the invention is to provide a firearm port block that can be used on most open port weapons.

Another object of the invention is to provide a firearm port block that will prevent users from placing live ammunition in the weapon's firing chamber until the weapon is ready for use.

Another object of the invention is to provide a gun safety device that will allow authorized users to operate the weapon within seconds.

Another object of the invention is to provide gun manufacturers an inexpensive means to secure weapons sold to the public.

BRIEF DESCRIPTION OF THE DRAWINGS

A more detailed understanding of the present invention may be had by reference to the following detailed description when taken in conjunction with the drawings wherein:

FIG. 1 is an elongated view of the firearm port block;

FIG. 2 is a view of the firearm port block in the compressed position;

FIG. 3 is a view of the firearm port block in the expanded position;

FIG. 4 is a view of the firearm port block, in a locked position, inside a weapons port. FIG. 4 drawing provides a view of the bolt ejector fastened over the raised rim of the firearm port block with the firing cap positioned in the weapon's firing chamber.

DETAILED DESCRIPTION OF THE DRAWINGS

In FIG. 1, an enlarged, elongated view of a firearm port block 3 is shown. The firearm port block 3 is a firearm safety device fitted to a firearms particular shell.

There are four operational parts to the firearm port block 3. (1) The shell canister 1, (2) a canister spring 4, (3) a tension (lock) screw 3a and (4) a canister locking tube 6. The shell canister 1 is a sized cylindrical hollow tube with a closed end 1a that has a raised shell rim 8 and a positioning tab 2. There are two fitted holes near the center of the shell canister 1, opposite each other, and is designed to receive the tension (lock) screw 3a. Opposite the closed end 1a is a hollow opening 1b. The length of the hollow opening 1b extends the length of the shell canister 1. The design of the open canister 1b is to receive the canister spring 4, the canister locking tube 6, the tension (lock) screw 3a and the tension nut 5.

The canister spring 4 is a hollow tension spring half the length of the shell canister 1. The canister spring 4 is positioned in the hollow portion of the shell canister 1. The end 4a of the canister spring 4 is against the inner side of raised shell rim 8 with end 4b extending half the length of the shell canister 1. The function of the canister spring 4 is to provide expansion and contraction for the canister locking tube 6.

The tension (lock) screw 3a is designed to lock the canister locking tube 6 in the expanded position (locked), FIG. 2 or contracted position (unlocked), FIG. 3. There are two parts to the locking system, the tension lock screw 3a and the tension nut 5. The tension nut 5 is positioned inside the canister locking tube 7a. When the tension nut 5 is placed in the canister locking tube 6 the end of the canister locking tube 6 is sealed 6a. The canister locking tube 6 is inserted into the shell canister 1, against canister spring 4 and by applying inward pressure the canister locking tube 6, align locking nut 5 and canister locking tube slot 7 with holes 5a and insert 3a through the canister shell 1, screwing 3a through the tension nut and the opposite hole of 5a. By loosening tension (lock) screw 3a it allows expansion of the canister spring 4, in turn expands the canister locking tube 6 and by turning tension (lock) screw 3a clock-wise, provides a locked position when inserted into a weapon's open port (FIG. 4, 14). By turning the tension (lock) screw 3a counter clock-wise and using the positioning tab 2, apply inward pressure toward the canister locking tube 6, the canister locking tube 6 will move against the canister spring 4, and by turning the tension (lock) screw 3a clock-wise, will allow contraction of the firearm port block 3 and provide clearance for removal of the firearm port block 3 from the weapons port 14.

The canister locking tube 6 is a cylindrical tube with a diameter size smaller than the diameter size of shell canister tube 1. The canister locking tube 6 is designed to traverse inside the tube of shell canister tube 1. There is a diagonal slot 7 on one side of the canister locking tube 6 with the slots 7 opening nearest the end that enters the open end of shell canister 1b. This diagonal slot 7 has a diameter size that allows the tension (lock) screw 3a to enter. The diagonal slot 7 allows for expansion and contraction of the canister locking tube 6 and provides a means to position the tube 6 in the locked or unlocked mode. The canister locking tube 6 has a closed end 6a that allows pressure to be applied by the canister spring 4. The canister locking tube 6 has a raised cap rim 8a that allows for stoppage of the firing chamber shell cap 9 when entering the weapon's firing chamber (FIG. 4, 10). The firing chamber shell cap 9 acts as a lock when expanded into a weapons firing chamber (FIG. 3, 9).

FIG. 2 is a side view of the Firearm Port Block 3 in the closed position. In this position the canister spring 4 is compressed by applying inward pressure to the canister locking tube 6 and tightening the tension lock screw 3a clockwise. By holding the positioning tab 2 the Firearm Port Block 3 may be inserted into the weapon's open port 14.

FIG. 3 is a side view of the Firearm Port Block 3 in the open position. In this position turning the tension lock screw 3a counter-clockwise, thus expanding the canister spring 4 that moves the canister locking tube 6 and inserts the firing chamber shell cap 9 into the weapon's firing chamber (FIG. 4, 10).

FIG. 4 is an oversized side view of a firearm 13 with the Firearm Port Block 3 in the expanded or locked position. In the aforementioned, the bolt 11 is in the shell extraction location of the open port 14 and the shell ejector 11a is positioned on the canister cap 1a of the Firearm Port Block 3. The canister spring 4 applies outward pressure against the canister locking tube 6 that expands the firing chamber shell cap 9 into the weapon's firing chamber 10, thus securing the firearm from being discharged. The tension (lock) screw 3a is rotated clockwise to the lock position. The tension (lock) screw 3a may use a keyed lock to maintain security.

What is claimed is:

1. What I claim as my invention is a firearm safety apparatus that prevents a weapon having a firing chamber, muzzle, and a barrel from being fired comprising, in combination:

a cylindrical device positioned snugly in a firearm's open port to prevent the insertion of a live round into said firing chamber;
a shell canister sufficient in length to support an elongated canister locking tube with raised rims on each end and when placed into the open port of a firearm, and expanded, prevents the firearm from being discharged;
a positioning tab attached to the shell canister which allows the user to place the firearm port block inside the open port to secure the firearm from being fired;

a firearm safety apparatus that has a canister spring within the shell canister for traversing the canister locking tube between an expanded locked position and a contracted unlocked position; and the canister locking tube having a raised cap supporting a raised rim to prevent the injection of live ammunition into a firearm-firing chamber;

said firearm safety apparatus is designed to fit all open port firearms.
